Primary Examiner — Christian P. McLean*Assistant Examiner* — D. Ryan Tisdale(74) *Attorney, Agent, or Firm* — Lewis Roca Rothgerber Christie LLP(57) **CLAIM**

The ornamental design for a decorative grille frame, as shown and described.

DESCRIPTION

FIG. 1 is a perspective view of the decorative grille frame;

FIG. 2 is a front view thereof;

FIG. 3 is a rear view thereof;

FIG. 4 is a bottom view thereof;

FIG. 5 is a top view thereof;

FIG. 6 is a left-side view thereof; and,

FIG. 7 is a right-side view thereof.

The ghosted or low contrasted showing of the decorative grille frame illustrate portions that form no part of the claimed design.
